Primary Examiner — Darlington Ly(74) *Attorney, Agent, or Firm* — Margaret Polson; Polson Intellectual Property Law, PC(57) **CLAIM**

The ornamental design for a grill, as shown and described.

DESCRIPTION

1. Grill

1.1 is a top, front, and left side perspective view of the grill showing my new design;

1.2 is a rear and left side perspective view thereof;

1.3 is a top plan view thereof;

1.4 is a front elevation view thereof; and,

1.5 is a right side elevation view thereof.

The broken lines are included for the purpose of illustrating environmental subject and form no part of the claimed design.

1 Claim, 5 Drawing Sheets(56)
